UNITED STATES PATENT OFFICE

163,631

TRAILER

Ben Newton Powell, Wasco, Calif.

Application January 30, 1950, Serial No. 7,569

Term of patent 14 years

(Cl. D14—3)

To all whom it may concern:

Be it known that I, Ben Newton Powell, a citizen of the United States, residing at Box 1386, in the city of Wasco, county of Kern, and State of California, have invented a new, original, and ornamental Design for a Trailer, of which the following is a specification, reference being had to the accompanying drawing, forming a part hereof.

Fig. 1 is a perspective view of a trailer, showing my new design.

Fig. 2 is a side elevational view thereof.

Fig. 3 is a top plan view of the trailer.

Fig. 4 is a front end view thereof.

One side only of the trailer is shown in the drawing, it being understood that the opposite side of the trailer is similar thereto.

I claim:

The ornamental design for a trailer, as shown and described.

BEN NEWTON POWELL.
